United States Patent Office

Des. 212,448
Patented Oct. 15, 1968

212,448

CAR BUFFER

Arthur Robert David Tosler, 7 Inglewood Ave.,
Bradmore, Wolverhampton, England

Filed Dec. 26, 1967, Ser. No. 9,913

Term of patent 14 years

Claims priority, application Great Britain June 30, 1967

(Cl. D66—2)

The single figure of the drawing is a perspective view, from above and from one side, of a car buffer showing my new design.

I claim:

The ornamental design for a car buffer, as shown.
